[57] CLAIM

The ornamental design for a combined ceiling fan and light, as shown and described.

DESCRIPTION

FIG. 1 is a perspective view of a combined ceiling fan and light embodying our design;

FIG. 2 is an enlarged front view thereof, the rear view being identical thereto;

FIG. 3 is an enlarged bottom view thereof; and,

FIG. 4 is an enlarged top view thereof.

Some of the fan blades in FIG. 2, and all of the fan blades in FIGS. 3 and 4 have been shown broken-away for ease of illustration.
